Primary Examiner — Jennifer L Rempfer*(74) Attorney, Agent, or Firm* — Pam Kohli Jacobson; K&L Gates LLP(57) **CLAIM**

The ornamental design for a sun dial towel, as shown and described.

DESCRIPTION

FIG. 1 is a perspective view of a sun dial towel.
 FIG. 2 is a top plan view of the sun dial towel of FIG. 1.
 FIG. 3 is a bottom plan view of the sun dial towel of FIG. 1.
 FIG. 4 is a left elevational view of the sun dial towel of FIG. 1.
 FIG. 5 is a right elevational view of the sun dial towel of FIG. 1.
 FIG. 6 is a rear elevational view of the sun dial towel of FIG. 1; and,
 FIG. 7 is front elevational view of the sun dial towel of FIG. 1.
 In all figures, broken lines illustrate environmental structures and form no part of the claimed design.

1 Claim, 5 Drawing Sheets(56)
